UNITED STATES PATENT OFFICE.

ROBERT B. WOOLVERTON, OF WASHINGTON, DISTRICT OF COLUMBIA.

TRANSMISSION OF RADIOSIGNALS EMPLOYING UNDAMPED WAVES.

Original application filed July 25, 1921, Serial No. 487,247. Patent No. 1,504,462, dated August 12, 1924.
Divided and this application filed December 10, 1923. Serial No. 679,850.

To all whom it may concern:

Be it known that I, ROBERT B. WOOLVERTON, a citizen of the United States, residing at Washington, District of Columbia, have 5 invented certain new and useful Improvements in Transmission of Radiosignals Employing Undamped Waves, of which the following is a specification.

This application is divisional from my co-pending application relating to transmission of radio signals employing undamped waves, Serial Number 487,247, filed July 25, 1921, issued as Patent No. 1,504,462, dated August 12, 1924.

15 This invention relates to improvements in radio transmission apparatus wherein a generator of persistent or undamped oscillations, such as an arc generator, high frequency alternator or other source of energy 20 is employed, and has for an object, the provision of transmitting apparatus of such arrangement as will permit of rapid fluctuations of the signal energy with the consequent production of sharp rapid signals at 25 a receiving station, a result impossible to be obtained satisfactorily by use of heretofore prevalent apparatus.

Other objects will be in part obvious and in part pointed out hereinafter.

30 In the employment of generators such as the arc and high frequency alternator, the method heretofore employed has been to connect the source of persistent oscillations directly in the antenna circuit in order to 35 make the over-all efficiency as high as possible. The interruptions in the antenna circuit were then produced by a variety of methods such as by varying the inductance in the antenna circuit by short-circuiting 40 the turns, or by connecting across the generator an oscillatory circuit having a lower resistance than the antenna circuit, so that by closing this oscillatory or local "tank" circuit by means of a key, practically all of 45 the generated radio frequency energy is diverted from the antenna circuit to the "tank" circuit. There are other means either employed or discarded, but all so far devised are unsatisfactory, because general- 50 ly the factors, necessary to be varied to produce variations in the antenna current, have been too great, and tend therefore to prevent rapid transmission.

Because of the constant advance in receiving apparatus, less energy need now be

generated in the antenna circuit to cover a given distance. Therefore, the over-all efficiency of a generator of radio frequencies is not paramount, this consideration giving ground to that of rapid transmission, a condition accomplished through the instrumentality 60 of my invention.

In order that the invention and its mode of application may be readily understood by persons skilled in the art, I have, in the accompanying 65 illustrative drawings, and in the detailed following description based thereon, set forth several embodiments of the same.

In the drawings—

Fig. 1 is a diagrammatic view of one form of a circuit provided with intelligence forming means, showing the resonance destroying means placed in the antenna circuit;

Fig. 2 is a diagrammatic view of a modification of that form of my invention shown in Fig. 1.

Instead of the arrangements shown in my copending application above referred to, it 80 is to be also understood that instead of placing the resonance destroying means in the socalled oscillatory circuit, the same may be as advantageously arranged in the antenna circuit of the apparatus as shown 85 in the Figure 1. Herein the oscillatory circuit is identified at 5' and is coupled, inductively, at 6' to the antenna circuit 8' which latter circuit has the coils of a variometer 16' connected in series therein as at 90 18; an arm 17' extends from one of said coils and has the armature of a solenoid 10^a connected thereto, whereby on the energization of the solenoid, the arm 17' will be caused to accordingly change the relative 95 positioning of the coils of the variometer. An intelligence forming circuit 12^a, corresponding to the circuits 12 and 12', is provided the solenoid 10^a, and obviously will afford means for effecting the shifting of 100 the arm 17'.

From the foregoing, it is to be understood that with the change in the relative positioning of the several coils of the variometer, the inductance of the antenna circuit 105 will be varied, and by consequence, resonance as between the same and the oscillatory circuit will be destroyed. Thus, the forming of intelligence or signals by this intermittent destruction of resonance be- 110

tween the oscillatory and antenna circuits, is rendered possible.

In the Figure 2 I have disclosed another arrangement of means for destroying resonance between the oscillatory and antenna circuits, wherein the antenna circuit 8' has a capacitance 19, arranged in the same, and about which a second capacitance 9' is shunted. To the movable element of the 10 capacitance 9', the armature of the solenoid 10^b is connected, being insulated therefrom as at 11'. The terminals of the solenoid 10^b are connected to the opposite sides of an intelligence forming circuit 12^b corresponding to the circuit 12^a and therefore, with closing of the key in said circuit, the solenoid 10^b will be energized, thus varying the positioning of the movable element of the capacitance 9' with relation to the fixed 20 element thereof whereby to vary or change the capacitance of the antenna circuit 8' and consequently destroy resonance as between said antenna circuit and the oscillatory circuit in order that the forming of intelligence or signals may be practically effected.

Manifestly, the arrangements shown

throughout are capable of considerable modification, and such modification as is within the scope of my claim, I consider within the spirit of my invention.

30

I claim—

In radio transmitting apparatus for undamped waves, an intelligence forming circuit including a solenoid, a tuned oscillatory circuit, shunted about the generator of 35 said transmitting apparatus, an antenna circuit inductively coupled to the tuned oscillatory circuit, said circuits being in exact resonance, a variable inductance connected in series in the antenna circuit, an arm for 40 connecting said variable inductance with said solenoid, and means for varying the relative positioning of the elements of said variable inductance for the purpose of energizing said solenoid and destroying the exact resonance between said oscillatory and antenna circuits, and thereby forming signals in said intelligence circuit.

In testimony whereof I affix my signature.

ROBERT B. WOOLVERTON.
